DESIGN FOR AN EMBROIDERED LACE TRIMMING OR SIMILAR ARTICLE

Jacob Nufer, West New York, N. J., assignor to Sol Wolfman, Inc., New York, N. Y., a corporation of New York

Application October 30, 1941, Serial No. 103,951

Term of patent 3½ years

To all whom it may concern:

Be it known that I, Jacob Nufer, a citizen of the United States, residing at West New York, Hudson County, and State of New Jersey, have invented a new, original, and ornamental Design for an Embroidered Lace Trimming or Similar Article, of which the following is a specification, reference being had to the accompanying drawing, forming part thereof, wherein the figure is a plan view of an embroidered lace trimming or similar article, showing my new design.

I claim:

The ornamental design for an embroidered lace trimming or similar article, substantially as shown.

JACOB NUFER.
